GAME

Arnold C. De Milt, Neenah, Wis.

Application September 20, 1938, Serial No. 230,865

3 Claims. (Cl. 273—141)

This invention relates to games, and its general object is to provide a game including a board having playing indicia thereon, a spinning disk rotatably mounted on the board and carrying a pointer which cooperates with the indicia on the board, the disk having areas thereon representing certain plays or the like, the board having a fixed pointer cooperating with the playing areas of the disk, so that upon rotation of the disk by a player, the plays can be determined by the pointers in conjunction with the board indicia and the playing areas of the disk.

A further object is to provide a game apparatus by which certain games can be played that are in simulation of well known outdoor games, such as baseball and football.

Another object is to provide a spinning disk mounting means for games of this character, whereby disks having different playing areas and/or indicia thereon are interchangeably associated with the mounting means for cooperation with the fixed pointer of the board, previously referred to, so that different games can be played, the mounting means including a handle for the disk and detachably associated parts, one carrying the disk and the other fixed to the board, and the disk carrying part being rotatably mounted on the fixed part, in a manner so that the disk can be readily spun with minimum effort but without fear of casual removal or displacement of the disk carrying part from the fixed part.

A further object is to provide a game which is capable of producing much fun and amusement for players of all ages, is simple in construction, inexpensive to manufacture and extremely efficient in use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

50 Figure 1 is a top plan view of the form of my game which is used for playing baseball.

Figure 2 is a sectional view taken approximately on line 2—2 of Figure 1, looking in the direction of the arrows.

55 Figure 3 is a top plan view of the board secured

bearing part of the spinning disk mounting means.

Figure 4 is a perspective view of one of the playing pieces or markers to be used with the apparatus as shown in Figure 1.

Figure 5 is a top plan view of a modified form of my game for playing football.

Referring to the drawings in detail, and particularly to the form as shown in Figures 1 to 4 inclusive, which illustrates the apparatus for playing the game of baseball, the reference numeral 1 indicates a game board which is shown as being of rectangular formation, but can be of any appropriate shape in outline providing it has a flat playing surface. The playing surface has printed or otherwise applied thereto spaced lines 2, one disposed within the other from the outer edge of the board to provide a strip like rectangular shaped margin or boundary 3, for a purpose which will be later described, and disposed midway between the ends of each of the side portions of the boundary strip are lines 4 bridging the lines 2 to provide blocks 5 for the bases that are simulated by a circular line 6 centrally arranged in each of the blocks, there being four blocks as shown, thus providing a first base, a second base, a third base and a fourth base or home plate, all of which are designated for that purpose, by words as shown.

Disposed within the boundary strip 3 are spaced lines 7 arranged in diamond formation to provide an area 8 to simulate a baseball diamond as will be apparent, and the outermost lines 7 extend from the inner ends of the lines 4 as shown, while the innermost lines 7 join each other at their ends midway between the innermost lines 4 and contact the innermost boundary line 2. It will be noted that the arrangement of the diamond area and the marginal area provide four triangular shaped areas 9, at the inner corners of the marginal area, and the areas 9 are numbered about the diamond area from right to left by the numerals one, two, three and four.

Disposed in the area 10 of the board within the diamond shaped area 8 and arranged parallel with the respective sides thereof are elongated blocked areas 11, the area 11 between the home plate and the first base having the word "Foul" designating the same, while the other areas 11 have the words "Foul and steal" designating the same, and are arranged midway between the remaining bases, as shown. The area 10 has also arranged therein elongated blocked areas 12, there being three blocked areas 12, one for each of the first, second and third bases as shown,

and the area 12 for the first base has the numeral one therein, the area 12 for the second base the numeral two and the area 12 for the third base by the numeral three. The areas 12 are disposed in alignment with their respective bases and extending from adjacent each of the areas 12 are arrows 13 that point to the bases as shown, while disposed between the bases and the respective areas 12 is the word "Out." There is also provided a blocked area 14 within the field area 10 between the sides of the diamond shaped area 8 that extend to the home plate, and the blocked area 14 is divided into three spaces, namely end spaces and a middle space, one end space having the numerals one and two therein, the middle space having the numerals one and three therein, and the other end space having the numerals two and three therein. The blocked area 14 also has the word "Out" disposed adjacent thereto, as well as what I term a fixed pointer 15 that extends through the blocked area, and is in the form of an arrow pointing toward the center of the board, for a purpose which will be later described.

Rotatably mounted with respect to the center of the board is a spinning disk 16 which is of circular formation and has a circular line 17 following the peripheral edge of the disk and disposed adjacent thereto, with crossed lines 18 dividing the peripheral edge portion of the disk between the line 17 and the edge, into four spaces 19, 20, 21 and 22. The space 19 has the word "Hit" therein, the space 20 the word "Strike" the space 21 the word "Ball" and the space 22 the word "Foul." Formed on and extending outwardly from the peripheral edge of the disk 16, is a triangular shaped projection 23 having its apex end outermost to provide a pointer, as will be apparent.

A scoring chart 24 is arranged on the board 1 at one end of the playing field as shown, and the chart 24 is of rectangular formation and divided by lines into parallel spaces 25 having the words "Runs," "Strikes," "Balls" and "Outs" at the left hand ends of the spaces, as shown.

In Figure 4 I have illustrated the game pieces or markers for use with the baseball game, and while these markers may be of any appropriate shape, they are shown as being in the form of disks 26, and are movable from base to base during the playing of the game along the boundary area, as well as for disposal in the spaces 24 for keeping the score, it being obvious that the markers may be supplied in groups of different colors, that is a group of one color for the players of one team or side and the group of another color for the players of the other team or side.

In playing the baseball game just described, official baseball rules are preferably used, and any number of players may participate, with the players divided into two sides. Of course, two players can play the game, each representing opposing teams.

It is believed that it will be obvious that the first player "at the bat" will place his marker on the home plate thence will rotate the spinning disk, to ascertain the play which is determined by the words in the spaces 19 to 22 respectively, in conjunction with the fixed pointer 15. In the event the disk 16 stops so that the pointer 15 indicates a hit play, the player must again spin or rotate the disk 16 and the result of the play will then be indicated by the pointer 23 and its position with respect to the blocked areas 11 and 12 and the spaces between the same in the

area 10. In the event the pointer 23 should indicate the foul blocked area 11, or in other words that blocked area between the home plate and the first base, such will represent a strike, but if the pointer 23 should stop in any portion of the area between the blocked areas 11 and 12, the hit will be completed, and in that area between the home plate and the first base the player will receive a "single," if between the first base and the second base, "a two base hit," between the second base and third base, "a three base hit," and between the third base and home plate, "a home run." However, if the pointer 23 should stop at any place between the ends of the areas 12, the player will be "out," as will be apparent. If a player has made a safe hit, with a marker on one of the bases, and a subsequent player spins the disk 16 and the pointer 23 stops between the ends of one of the blocked areas 11 having the words "Foul and steal" thereon, the player having his marker on the base will advance one base and the player making the hit will receive a "Strike." It will be obvious that when a player receives three strikes he is out. If the disk 16 stops so that one of the lines 18 between the spaces 19 to 22, is aligned with the pointer 15, such represents a "Ball," and it will be further obvious that the Runs, Strikes, Balls and Outs are kept on the scoring chart by additional markers or disks 26. The numerals in the blocked area 14 indicate double and triple plays, that is in the event a player has a marker on first base, and a subsequent player makes a hit, and thence the pointer 23 stops at a point to indicate the end space having the numerals one and two therein, the player making the hit, as well as the player having the marker on the first base is out, or in other words a double play has been completed. A triple play is of course made between the first and third bases, and in that event the pointer 23 must stop between the ends of the space having the numerals one and three therein, and when the pointer stops between the ends of the space having the numerals two and three therein, a double play is made between second and third base, it being apparent that the players must be on the respective bases when making the plays stated. If by chance the pointer 20 on the second spin should stop in alignment with the pointer 15, the player must necessarily spin the disk again.

The football game as shown in Figure 5 likewise includes a game board 27 that has a circular area provided by concentrically disposed heavy lines 28, which are likewise concentrically arranged with respect to the center of the board and heavy lines 29 extend between the lines 28 at unequal distances apart to divide the circular area into goal spaces 30 disposed diametrically opposite each other, gain spaces 31, no gain spaces 32 and loss spaces 33. The goal spaces are diametrically disposed with respect to each other, and one of the spaces 30 has the words "North goal" therein while the other space has the words "South goal" therein. The gain spaces have their respective numerals five, ten, fifteen, twenty and twenty-five therein. The no gain spaces are disposed between the gain spaces and the loss spaces, and have the words "No gain" therein, while the loss spaces are disposed diametrically opposite each other or in other words midway between the spaces 30 and the loss spaces have the numerals five, fifteen and ten therein respectively, as shown.

The heavy lines of the circular area on one

side of the goal spaces and including the lines of one goal space are printed or otherwise applied in one color such as blue, and the heavy lines on the opposite sides of the goal spaces 5 including the lines of the other goal space are printed or otherwise applied in another color such as red, and it will be obvious that such will provide separate and distinct area spaces which may be termed playing fields that can be readily 10 distinguished from each other due to the contrasting colors.

Extending across the south goal space is a stationary pointer 35 in the form of an arrow as shown, that points in the general direction of 15 the center of the game board, and rotatably mounted in the center is a spinning disk 36 which is divided into half portions of contrasting colors, the portion 37 being colored blue as shown, while the portion 38 is colored red. Formed on and extending outwardly from the peripheral edge of 20 the spinning disk 36 is a pointer 39.

The football game may be played by two players, each representing a football team. One player selects one color, and the other another color, such as for instance blue and red, the colors being showing in the drawings. After selecting the colors, one player then spins the disk 36 and the color which is opposed to the stationary pointer 35 indicates the player who starts the 25 game. The game may be divided into four quarters, and there may be ten or more plays in each quarter, the players deciding how many plays they wish to make before starting the game. Each spin of the disk 36 represents a play and 30 the plays are made on the opponents colors, for example the player who has selected red starts the game by spinning the disk. If the disk stops so that the blue colored area thereof is indicated by the stationary pointer 35, thence the player 35 notes at what space or section of the circular area the pointer 39 indicates, as the latter pointer indicates the gains and losses in yards that have been made by the play, as well as no gain as will be apparent, and as the disk has stopped 40 with the stationary pointer indicating the blue area thereof, the first player is still privileged to play, as he has what may be termed possession of the ball and may therefore spin the disk again. He may spin as many times in succession as his 45 color is indicated by the stationary pointer. However, when the stationary pointer indicates the opponents color or red, the first player loses what may be termed possession of the ball and the second player then takes his turn. It is believed 50 that it will be obvious that in the event the pointer 29 should indicate the opponents goal space or section, that the player is entitled to six points or a touchdown, and the player is entitled to spin the disk again. After the second 55 spin the opponents colored area on the disk 36 should be indicated by the stationary pointer 35, the player receives an extra point or in other words a kick after touchdown, but the extra point is not received if the stationary pointer indicates 60 the players colored area of the disk. It will be further obvious that in the event a player gains fifty yards he is likewise entitled to six points or a touchdown and then spins the disk to ascertain if he is entitled to the extra point.

The mounting means for the spinning disks is of utmost importance, and is clearly shown in Figure 2. It includes a stationary part provided with a disk-shaped base 40 for disposal on the underside of the game board, and which has a plurality of penetrating prongs 41 formed

on and extending upwardly from the periphery thereof for disposal within the board, as shown. Formed on and rising centrally from the base 40 for disposal through an opening in the board, is a stud 42 threaded for a portion of its height 5 from its juncture with the base, to receive a ring nut 43 for securing the stationary bearing part to the board, and the upper end of the stud is shaped in conical formation to provide a bearing. The upper or rotating bearing part of the 10 spinning disk mounting includes a flat body member 44 having a skirt 45 depending therefrom, with a conical inner end providing a seat for the pointed end of the stud, for the upper part to rotative thereon, as will be apparent upon 15 inspection of Figure 2 and formed on and rising centrally from the body member 44 is a threaded stud 46 for receiving a spinning disk, the latter having an opening centrally arranged therein for that purpose, and is held against the body member 20 by a knob 47 threaded on the stud 46, and a washer 48 is disposed between the spinning disk and the knob. By that structure, it will be obvious that the knob provides a handle for spinning the disk and as the skirt is of a 25 diameter to fit the stud 42, the disk is held against wobbling movement during its spinning action, and casual removal or displacement of the upper part is practically impossible, yet the disk is freely spun due to the pointed upper end of the stud 30 42 and the seat therefor.

It will be further obvious that the spinning disk is removably associated with the mounting means, and while I have illustrated two spinning disks one for use with a baseball game and the other for a football game, I may provide disks having other playing indicia or areas thereon for cooperation with the stationary pointer on the game board for playing different games, that is a series of spinning disks may be provided with 35 each game for interchangeable association with the mounting means. For example another spinning disk may have the letters of the alphabet 40 thereon for playing what I call a spelling game which is played by the players first selecting a 45 word to spell, thence the players spin the disk in turn and mark down upon a paper, scoring means or the like the letters required to form the word, as the letters are indicated by the stationary pointer. The player who first succeeds in obtaining all of the letters required to spell the 50 word he selects, wins the game. Another disk may have numbered characters thereon, such as figures or runners, airplanes, racing automobiles, etc., thereon for playing what I call a racing 55 game, and in that event two or more players will select a character and one player will then spin the disk. The player selecting the character which is indicated by the stationary pointer when the disk stops, wins the game.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A game comprising a board having separated indicia thereon, a spinning disk, rotatably associated bearing means for the disk and secured thereto and the board respectively, lines on said disk and dividing the same into visually 70 distinguishable areas, a pointer carried by the 75

disk to identify any of the board indicia when the disk comes to rest, a stationary pointer fixed to the board to identify a particular area on the disk when the latter comes to rest, so that upon rotation of the disk the plays of the game are determined by the pointers in conjunction with the board indicia and the disk areas.

5. A game comprising a square cornered board marked by circular concentrically disposed lines 10 and lines between the circular lines to provide separate spaces disposed concentrically with respect to the center of the board indicia in each of said spaces, half of the space lines being of one color and the other half another color, a 15 spinning disk, handled rotatably associated bearing means for the disk and secured thereto and the board respectively for rotation of the disk concentrically with respect to the spaces, said spinning disk having one-half of the area there- 20 of of one color and the other half of another color and the colors corresponding to those of the space lines, a pointer carried by the disk to identify any of the indicia when the disk comes to rest, a stationary pointer in the form of an 25 arrow marked on the board to identify any one

of the colored areas of the disk, so that upon rotation of the disk by a player, the plays of the game are determined by the pointers in conjunction with the indicia and the colored areas.

3. In a game including a board and a spinning disk, mounting means for the disk and comprising a disk-shaped base engaged with the underside of the board, a threaded stud formed on and rising centrally from the base and extending through the board, means threaded on the stud, 10 upright penetrating prongs formed on the periphery of the base and embedded in the board for cooperation with said threaded means for securing the base to the board, a conical upper portion for the stud and providing a pointed bearing, 15 a flat body, a skirt depending from the body and surrounding the stud, said skirt having a conical inner end receiving the pointed bearing therein for rotation of the body thereon, a threaded stud rising from the body and receiving the disk there- 20 on, and a knob providing a handle threaded on the second stud for detachably securing the disk to the body.

ARNOLD C. DE MILT. 25
